UNITED STATES PATENT OFFICE.

GEORGE S. KNAPP, OF LA GRANGE, ILLINOIS, ASSIGNOR TO KNAPP BROTHERS MANUFACTURING COMPANY OF CHICAGO, ILL., OF CHICAGO, ILLINOIS, A CORPORATION OF ILLINOIS.

METAL BASE-BOARD.

1,205,358.

Specification of Letters Patent. Patented Nov. 21, 1916.

Application filed September 7, 1915. Serial No. 49,310.

To all whom it may concern:

Be it known that I, GEORGE S. KNAPP, a citizen of the United States, residing at La Grange, in the county of Cook and State 5 of Illinois, have invented certain new and useful Improvements in Metal Base-Boards, of which the following is a specification.

My invention relates to improvements in metal base boards and has especial reference 10 to means and appliances for joining adjacent ends of sections of such boards.

The object of my invention is to generally improve devices of this character.

Other and further objects of my invention 15 will become obvious, to persons skilled in the art, from a consideration of the following description when taken in conjunction with the drawings, wherein:

Figure 1 is an isometric perspective of a 20 portion of one section of the board and a connecting fitting for adjoining sections for continuing the face surface of the sections around an inside corner. Fig. 2 is a section of the finished wall after the plaster has 25 been applied thereto. Fig. 3 is a section taken on line 3—3 of Fig. 5. Fig. 4 is a section taken on line 4—4 of Fig. 5. Fig. 5 is a section taken on line 5—5 of Fig. 4.

In all the views the same reference characters are employed to indicate similar 30 parts.

In my Patent No. 1,143,283 granted to me June 15th, 1915, I have shown, but not claimed, means for joining contiguous metal 35 base board sections. In this, my present application, the claims are directed to the casting, or fitting for connecting proximate ends of the sheet metal base board sections at corners of a room.

40 In the present embodiment the adjacent sections of the board are designed and intended to be secured to the angle plate or fitting before the assembled parts are fastened to the wall.

45 In the illustration 10 is a sheet metal base board, having a vertical plane face portion 11 and curved face portion 12. It is provided with the mortar receiving perforations 13 and 14 for introduction of the mortar or plaster behind the face of the board 50 as more clearly shown and claimed in my former patent.

The upper margin 15 is provided with 55 perforations 16 and 17 for attaching the board to the side, while the lower portion of

the board is provided with a margin 18 that is to be in contact with the wall, having perforations 19 and 20. The upper margin is inturned, as at 21, and the lower margin is downturned, as at 22. An angle casting, or fitting 23, is provided with a vertical curved surface 24 which is practically a continuation of the surface 11 of the section 10, and an outwardly curved surface 25, which is practically a continuation of the curved surface 12 of the section 10. The surfaces 24 and 25 project forwardly of the surface 26, to an extent equal to the thickness of the material of which the section 10 is composed 60 so that the part 26 serves as a backing for the part 11 of the strip. Projections 27 and 28 extend laterally of the part 26 and above the part 27 is an ear 29 having a perforation 30 and separated from the part 27 by a slot 31. The part 21 of the board enters the slot 70 31 of the fitting and a screw 32 passes through the perforation 30 of the fitting and through a similar perforation of the part 15 of the board, thereby holding the fitting in contact with adjacent edges of a board section. Similar screws 33 pass through the lower portion of the board member and into 75 perforations 34, contained in the lower edge of the parts 26, 27 and 28 of the fitting, thereby securely holding the fitting at top 80 and bottom limits to the attached base board section. A curved perforation 35, within which to key the plaster, is made in the upper portion of the fitting, the edge 36 serving as a ground to which the plaster is 85 finished.

The floor may be finished to the upper edge 37 of the part 22 or to the lower edge 38 as desired. If it is a composition floor, as shown in Fig. 2, it is preferably finished 90 to the upper edge 37, so that the mortar, or other composition, may pass through the perforations 14 behind the lower portions of the board.

It will be observed that the upper edge of 100 the board passes behind the fitting 23 while the lower edge is secured by the same means in front of the fitting. By this means the fitting is held in place against the wall by the fastenings 39 that pass through the body 105 portion of the board and at the lower edge the fitting is supported by the shoulder 40 of the board section. Thus the shoulders provided at the upper and lower ends of the fittings prevent transverse shifting of 110

the parts after they have been placed in position.

Having described my invention, what I claim is:

- 5 A fitting for joining sections of sheet metal base boards having upper and lower longitudinal marginal portions bent rearwardly and then outwardly into the same plane for attachment to a wall, said fitting
- 10 comprising a body part having a face surface shaped to form a continuation of the exposed surface of the base board, integral end numbers projecting from the body part to underlie the rear face of the base board
- 15 intermediate its marginal portions, projections extending from the body part near its

upper end and spaced vertically from the end numbers to form horizontally extending openings therebetween to receive the upper rearwardly extending marginal portion of 20 the base board, the upper outwardly bent edge portion of the base board lying at the rear of the projections, and fastening means taken through the projections and outwardly bent edge portions of said base board.

25

In testimony whereof I hereunto set my hand in the presence of two subscribing witnesses.

GEORGE S. KNAPP.
